UNITED STATES PATENT OFFICE.

JOHN EDWARD LANGLEY, OF CHARLESTON, SOUTH CAROLINA.

SHOWER-BATH APPARATUS.

1,054,572.

Specification of Letters Patent. Patented Feb. 25, 1913.

Application filed May 21, 1912. Serial No. 698,704.

To all whom it may concern:

Be it known that I, JOHN EDWARD LANGLEY, a citizen of the United States, and a resident of Charleston, in the county of Charleston, State of South Carolina, have invented a new and useful Improvement in Shower-Bath Apparatus, of which the following is a specification.

My invention is an improvement in shower bath apparatus, and has for its object the provision of a metal, economical portable, extension shampoo, and shower attachment, with practically no wearing parts, one that can be closed so as to permit of being carried in an ordinary suit case, easily and quickly attached to any standard combination hot and cold water cock, and extended to provide for the desired bath.

Another object of my invention is to provide an economical extension combination shampoo and shower bath attachment constructed of metal with practically no wearing parts that can be readily and quickly attached to any standard combination hot and cold water cock, and easily extended and held in place secure at the desired height without the use of screws or any means of support other than that afforded by the fixture itself, and which can, through the removal of the shower head, be used as a simple extension cock, and thus meet all the requirements of a lavatory or basin without any cost other than that of the attachment.

Another object of my invention is to provide an ornamental fixture of graceful design that can be installed in connection with any lavatory and serve two purposes, that of an ordinary cock, through removal of shower head, and a shampoo cock through the addition of shower head, with the added properties of being able to extend same to suit any head, and to direct spray at any desired angle, thus doing away with two sets of fixtures as at present employed.

In the drawings: Figure 1 is a perspective view of the improvement in place; Fig. 2 is a top plan view of the spraying mechanism partly in section; Fig. 3 is an enlarged detail longitudinal section of the connection between the sections of the apparatus; and, Fig. 4 is a plan view of the holding means for the pipe sections.

The present embodiment of the invention is shown applied to the common outlet 1 of the hot and cold water pipes 2 and 3, re-

spectively, of a bath tub 4. The improvement comprises a siphon shaped pipe consisting of a long arm or portion 5 and a short arm or portion 6. The portion 6 of the pipe is provided with a union 7 for connecting the pipe with the inlet, and the portion 5 of the pipe is arranged between the valves 8 and 9 of the hot and cold water pipes and between the inlet 1 and the adjacent side of the tub. The portion 6 of the pipe extends directly downward from the inlet 1 and the arch 10 connecting the two portions extends toward the end of the tub, so that the portion 5 is entirely out of the way of the occupant of the tub when bathing in the usual manner.

The pipe 5—6—10 is the lower section of the apparatus and is connected to the upper section, comprising a pipe 11 provided at its upper end with branches 12 and 13 by means of the connection shown more particularly in Fig. 3. The pipe 11 is of smaller diameter than pipe 5 and is fitted at its lower end into the upper end of the said pipe 5. The upper end of pipe 5 is externally threaded and is engaged by collar 14, internally threaded at its lower end for engaging pipe 5, and having its upper end reduced internally, as shown at 15, to engage pipe 11.

The upper end of the collar is externally threaded, as shown at 16, and is annularly enlarged internally, as shown at 17, and a gasket or packing ring 18 is arranged in the enlargement, the said ring or gasket encircling the pipe 11. A cap or nut 19 encircles the pipe 11 above the collar, and the said nut is provided with a marginal encircling threaded flange 20 for engaging the threaded portion 16 of the sleeve. The said nut or cap is also provided with an annular rib 21 adjacent to the pipe 11 and engaging the gasket, for compressing the same to cause the said gasket to grip the pipe 11.

A clamping device encircles the pipe 11 above the cap or nut, to hold the said pipe or nut in adjusted position. The said device comprises oppositely arranged clamping members each of which consists of a handle portion 22, and an arc-shaped clamping member 23, and the said portions 23 coöperate to get the pipe between them. Each of the portions 23 is provided with a lining or facing 24 of suitable material, to enable the said portions to grip the pipe firmly without marring or scratching the

same. A substantially V-shaped plate spring 25 is arranged between the handle portions 22 of the clamping member, and each arm of the said spring is riveted to the inner face 5 of the portion 22 of the adjacent clamping member by rivets 26. The spring is arranged to permit the handle portions 22 of the clamping members to be moved together to move the portions 23 away from the pipe 10 to release the same.

When the clamping members are released as above mentioned the pipe 11 may be moved longitudinally, sliding through the sleeve 14 and the gasket 18. The pipe 11 is 15 not only slidable in the pipe 5, but is also rotatable in the said pipe whatever its position with regard to the said pipe. The branches 12 and 13 of pipe 11 are curved, as shown more clearly in Fig. 2, each being 20 of approximately semicircular shape, and at the end remote from the pipe 11 each branch is connected to one end of a T 29 by means of a union 30. The ends of branches 12 and 13 are enlarged and externally threaded at 25 31, and each of the ends of the T is provided with an annular rib 32. The union 30 clamps the shoulder or rib 32 against the annular enlargement 31, and the ends of the branches are recessed, as shown, to receive the ends of the T. The lateral branch 33 of the T has threaded thereinto the nipple 34 of a shower or spraying head 35. The T with the head is rotatable with respect to the branches 12 and 13, so that the head 35 35 may be directed laterally, upwardly and downwardly, or in the intermediate positions.

With the parts in the position shown in Fig. 1, the head 35 may be raised or lowered 40 with respect to the tub by pulling or pushing on the pipe 11, and the head may also be revolved around the pipe 11 and may be swung to direct the spray in any desired direction for any form of bath. When the 45 head 35 is removed, the device is merely an extension of the inlet 1 and may be used to direct a stream instead of a shower. When not in use, the pipe 11 may be telescoped into pipe 5, thus making a very 50 compact device for storage or transportation.

A T 36 has its lateral branch 37 engaged with the upper end of the pipe 11, and the ends of the T are connected by unions 38 55 with the branch pipes 12 and 13 before mentioned.

I claim:

1. An apparatus of the character specified, comprising a pipe composed of two substantially parallel portions of unequal 60 length connected at one end, the free end of the short portion having means for connecting it to the common inlet of a bath tub, a second pipe slidable at one end in the long portion of the first pipe and rotatable 65 with respect thereto, said second pipe having a pair of diverging branches at the other end, said branches curving outwardly and again inwardly, a T connecting the free or outer ends of the branches and rotatable on 70 the branches, and a spray head connected to the lateral branch of the T, and means for securing the said pipes in adjusted position.

2. An apparatus of the character specified, comprising a pipe composed of two 75 substantially parallel portions of unequal length connected at one end, the free end of the short portion having means for connecting it to the common inlet of a bath tub, a second pipe slidable at one end in the long 80 portion of the first pipe and rotatable with respect thereto, means for securing the pipes in adjusted position, said second pipe having branches at its upper end, the branches being curved outwardly away from each 85 other, and a spray head rotatably connected with the free ends of both branches.

3. An apparatus of the character specified, comprising a pair of telescoping pipes, means for securing the pipes in adjusted 90 position, one of the said pipes having a return portion at its outer end provided with means for engaging the common inlet of a bath tub, a shower or spraying head, and means for engaging the said head to the 95 outer end of the other pipe, to permit the head to swing and to rotate with respect to the said other pipe.

4. An apparatus of the character specified, comprising a pair of telescoping pipes 100 and means for securing the pipes in position, one of the pipes having means for permitting it to be connected with the common inlet of a bath tub, a shower or spraying head provided with a T, and means for rotatably connecting the ends of the T to the other pipe.

JOHN EDWARD LANGLEY.
